UNITED STATES PATENT OFFICE.

JOSIAH H. SMITH, OF PHILADELPHIA, PENNSYLVANIA, ASSIGNOR TO WILLIAM H. TIGERMAN, OF PHILADELPHIA, PENNSYLVANIA.

SUSPENSION-RAILWAY.

1,138,697.

Specification of Letters Patent. Patented May 11, 1915.

Application filed August 19, 1914. Serial No. 857,475.

To all whom it may concern:

Be it known that I, JOSIAH H. SMITH, a citizen of the United States, residing at Philadelphia, in the county of Philadelphia and State of Pennsylvania, have invented 5 certain new and useful Improvements in Suspension-Railways, of which the following is a specification.

My invention relates to improvements in 10 suspension railways, the object of the invention being to provide improved elevated rail supports which are especially adapted for suspension railways of the monorail type.

A further object is to provide a longitudinal 15 girder or girders with laterally projecting cantalivers supporting at their outer ends an I-beam upon which the truck supporting rail is mounted.

A further object is to provide improvements 20 of the character stated which embody in their construction, simplicity, durability, and the maximum of strength to withstand strains and stresses to which such parts are necessarily subjected.

With these and other objects in view, the 25 invention consists in certain novel features of construction and combinations and arrangements of parts as will be more fully hereinafter described and pointed out in the 30 claims.

In the accompanying drawings: Figure 1 is a fragmentary view in side elevation illustrating my improvements. Fig. 2 is a view 35 in transverse section. Fig. 3 is an enlarged view in transverse section through the longitudinal girders. Fig. 4 is a view in horizontal transverse section on the line 4—4 of Fig. 3. Fig. 5 is a view in vertical section on the line 5—5 of Fig. 3.

40 1—1 represent longitudinal girders supported by transverse girders 2 located at the upper ends of uprights 3, and said longitudinal girders are located parallel to each other, spaced apart, and strengthened by 45 any suitable sway bracing 4 to hold the girders properly spaced and to strengthen them against lateral strains and stresses.

The longitudinal girders 1 are alike, and 50 the description hereinafter of one will apply alike to both. Each longitudinal girder 1, at its upper edge, is provided with a pair of longitudinally positioned angle bars 5 constituting the upper cord of the beam, and between which at regular intervals, gusset 55 plates 6 are secured. The lower cord of the

longitudinal beam is formed by a pair of angle bars 7 secured at opposite sides of a longitudinal plate 8, and the gusset plates 6 and longitudinal plate 8 are connected by diagonal struts 9 and vertical struts 10. 60 These struts 9 and 10 are preferably angle bars, and the vertical struts 10 are arranged in pairs and constitute points of intersection along the girder. At such points of intersection, I provide by improved laterally projecting cantalivers 11, the description hereinafter of one applying alike to all. Between the vertical angle bar struts 10, at the points of intersection, I secure triangular shaped plates 12. These plates 12 are preferably shaped as shown, that is, their lower edges are horizontal and their upper edges are inclined downwardly from their inner to their outer ends.

The upper and lower edges of the plates 75 12 are strengthened by angle bars 13 and 14 respectively, which are securely riveted to the plates and to the vertical struts 10 as clearly shown in Fig. 3. At the outer ends of the plates 12, I secure angles 15 80 which are also secured to the webs of longitudinal I-beams 16, and said I-beams are secured by plates 17 to the angle bars 7 forming the lower cord of the longitudinal beam. These plates 17 are also triangular 85 in shape with their wider ends located under and secured to the bars 7 as shown clearly in Fig. 4, and such plates serve to prevent any lateral movement of the cantaliver or longitudinal movement of the I-beam. The I- 90 beams support on their upper edges, rails 18 to receive the double flanged wheels 19 of trucks 20 supporting the cars 21 suspended therefrom.

The longitudinal girders 1 are connected 95 to the transverse girders 2 by means of shear plates 22. These shear plates are located at opposite sides of the transverse girders and extend between the parallel angles 6 constituting the upper cord of the longitudinal 100 girder and between the angle bars 7 forming the lower cord of the longitudinal girder.

The plates 22, which are secured to the transverse girders 2, are securely riveted to 105 the bars 6 and 7. They are strengthened at their edges by angle bars 23, and are also connected to the longitudinal plates 8 by means of diagonal struts 24. In other words, the plates 22 are positioned between 110

the pairs of angle bars 6 and 7, and constitute not only coupling means for the longitudinal and transverse girders, but also strengthen both the longitudinal and the 5 transverse girders, and insures a rigid junction of the parts.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

15 Having thus described my invention, what I claim as new and desire to secure by Letters Patent is:

1. In a suspension railway, the combination with a longitudinal girder, of a series 20 of laterally projecting rail supporting cantalivers secured to the longitudinal girder and horizontal plates below the cantalivers secured to the girder, substantially as described.

25 2. In a suspension railway, the combination with a longitudinal girder, of laterally projecting cantalivers on the girder, a longitudinal rail supporting beam secured to the cantalivers and means connecting the 30 beam with the bottom of the girder, substantially as described.

3. In a suspension railway, the combination with a longitudinal girder, of laterally projecting cantalivers on the girder, a longitudinal rail supporting beam secured to the cantalivers, and horizontally positioned plates connecting the lower edge of the beam with the lower edge of the longitudinal girder, substantially as described.

40 4. In a suspension railway, the combination with a longitudinal girder, of cantalivers projecting laterally from the girder, an I-beam secured to the outer ends of the cantalivers, a rail supported upon the I-beam, 45 and plates connecting the I-beam with the bottom of the girder below the cantalivers, substantially as described.

5. In a suspension railway, the combination with a longitudinal girder consisting of 50 upper and lower parallel angle bars connected by vertical and diagonal angle bar struts, said vertical angle bars arranged in pairs, of laterally projecting vertically positioned plates secured between the pairs of vertical 55 struts, and rail supporting beams secured to the outer ends of said plates, substantially as described.

6. In a suspension railway, the combination with a longitudinal girder consisting of 60 upper and lower parallel angle bars connected by vertical and diagonal angle bar struts,

said vertical angle bars arranged in pairs, of laterally projecting vertically positioned plates secured between the pairs of vertical struts, angle bars secured to the plates at 65 their upper and lower edges at opposite sides, angles secured to the opposite sides of the plates at their outer ends, and a rail supporting beam secured to the last-mentioned angles, substantially as described. 70

7. In a suspension railway, the combination with a longitudinal girder consisting of upper and lower parallel angle bars connected by vertical and diagonal angle bar struts, said vertical angle bars arranged in 75 pairs, of laterally projecting vertically positioned plates secured between the pairs of vertical struts, angle bars secured to the plates at their upper and lower edges at opposite sides, angles secured to the opposite 80 sides of the plates at their outer ends, a rail supporting beam secured to the last-mentioned angles, and plates connecting the lower face of the beam with the lower face of the girder and located below the first-85 mentioned plates, substantially as described.

8. In a suspension railway, the combination with uprights, transverse girders connecting the uprights, longitudinal girders secured to and suspended from the transverse girders, cantalivers secured to the longitudinal girders, I-beams secured to the cantalivers, and rails supported upon the I-beams, substantially as described. 90

9. In a suspension railway, the combination with a plurality of transverse girders, of parallel longitudinal girders, each longitudinal girder consisting of upper and lower parallel angles, struts connecting the angles, shear plates secured between the angles and connecting the same to the transverse girders, and laterally projecting rail supports on said girders, substantially as described. 95

10. In a suspension railway, the combination with a plurality of transverse girders, of parallel longitudinal girders, each longitudinal girder consisting of upper and lower parallel angles, struts connecting the angles, shear plates secured between the angles and connecting the same to the transverse girders, sway bracing connecting the longitudinal girders, and laterally projecting cantaliver rail supports projecting outwardly from said girders, substantially as described. 100

110 In testimony whereof I have signed my name to this specification in the presence of two subscribing witnesses.

JOSIAH H. SMITH.
